UNITED STATES PATENT OFFICE.

CORODON S. CANNON, OF LIGONIER, INDIANA.

BARREL-HOOP.

SPECIFICATION forming part of Letters Patent No. 377,799, dated February 14, 1888.

Application filed December 19, 1887. Serial No. 258,326. (No model.)

To all whom it may concern:

Be it known that I, CORODON S. CANNON, a citizen of the United States, residing at Ligonier, in the county of Noble and State of Indiana, have invented a new and useful Improvement in Barrel-Hoops, of which the following is a specification.

My invention relates to improvements in barrel-hoops; and it consists in certain novel features, hereinafter described and claimed.

In the accompanying drawings, which fully illustrate my invention, Figure 1 is a perspective view of a portion of a barrel provided with my improved hoop. Fig. 2 is a plan view of the fastening, and Fig. 3 is an edge view of the same.

Referring to the drawings by letter, A designates the barrel, and B the hoop secured around the same. The said hoop consists of the strap C and the loops or rings D, secured to the ends of the same. These rings or loops are preferably triangular in form, with their apices projecting from the ends of the strap. The ends of the strap are provided with tongues E, which are bent around the base of the triangular loop, and then riveted to the main portion of the strap, as clearly shown in Figs. 2 and 3. In order that there may be no lateral movement of the loops or rings, I construct in the bases of the same the angular extensions or projections F, which form the parallel shoulders G, between which the edges of the tongues E rest when passed around the extensions F, as shown in Fig. 2.

In practice the strap is passed around the barrel, the loops and the ends of the strap being brought close together, causing the strap to bind around the barrel. The two loops are then securely fastened by means of a tie-wire, H, passed alternately through and around each of the same, as clearly shown.

The strap is made of strong flexible metal, and can consequently be applied to a barrel of any diameter. The device can be extended in a straight line, so that a large number can be packed in a small space for storage or transportation.

The simplicity and cheapness of the device are evident and its advantages are thought to be obvious.

The open space between the strap and loop is thought to be of advantage when handling and adjusting the ends of the hoop on the barrel.

Having thus described my invention, what I claim, and desire to secure by Letters Patent, is—

1. A barrel-hoop consisting of a flexible strap, the loops or rings secured to the ends of the straps, and a tie-wire passed around and alternately through said loops, substantially as set forth.

2. A barrel-hoop consisting of a flexible strap, the loops or rings having extensions to receive the ends of the strap, and a tie-wire passed through and around said loops or rings, substantially as specified.

3. A barrel-hoop consisting of a flexible strap having tongues at its ends, loops or rings having extensions through and around which said tongues are passed, and a tie-wire for securing said loops or rings, substantially as described and shown.

In testimony that I claim the foregoing as my own I have hereto affixed my signature in presence of two witnesses.

CORODON S. CANNON.
